(57) **CLAIM**

I claim the ornamental design for a pillowcase, as shown and described.

DESCRIPTION

FIG. 1 is a perspective view of one embodiment of a pillowcase showing the new design.

FIG. 2 is a top view thereof.

FIG. 3 is a bottom view thereof.

FIG. 4 is a front elevational view thereof.

FIG. 5 is a rear elevational view thereof.

FIG. 6 is a right side elevational view thereof.

FIG. 7 is a left side elevational view thereof.

FIG. 8 is a perspective view of an alternative embodiment of a pillowcase.

FIG. 9 is a top view thereof.

FIG. 10 is a bottom view thereof.

FIG. 11 is a front elevational view thereof.

FIG. 12 is a rear elevational view thereof.

FIG. 13 is a right side elevational view thereof.

FIG. 14 is a left side elevational view thereof.

FIG. 15 is a perspective view of an alternative embodiment of a pillowcase.

FIG. 16 is a top view thereof.

FIG. 17 is a bottom view thereof.

FIG. 18 is a front elevational view thereof.

FIG. 19 is a rear elevational view thereof.

FIG. 20 is a right side elevational view thereof.

FIG. 21 is a left side elevational view thereof.

FIG. 22 is a perspective view of an alternative embodiment of a pillowcase.

FIG. 23 is a top view thereof.

FIG. 24 is a bottom view thereof.

FIG. 25 is a front elevational view thereof.

FIG. 26 is a rear elevational view thereof.

FIG. 27 is a right side elevational view thereof; and,

FIG. 28 is a left side elevational view thereof.
